INVENTOR

BY Victor J. Evans

ATTORNEY

J. B. Baker, Jr.
WITNESS:

UNITED STATES PATENT OFFICE.

FRANK F. SEIDTS, OF BRYN MAWR, PENNSYLVANIA.

LABEL HOLDER.

Application filed February 15, 1922. Serial No. 536,726.

To all whom it may concern:

Be it known that I, FRANK F. SEIDTS, a citizen of the United States, residing at Bryn Mawr, in the county of Montgomery and State of Pennsylvania, have invented new and useful Improvements in Label Holders, of which the following is a specification.

This invention relates to label holders and it has more particular reference to devices or means for use in association with plant designating devices, said devices being devised with the object of giving a visible indication as to the nature of a plant, tree 15 or shrub in a manner that will be effectively preserved from deterioration by the elements.

The primary object of my invention is to provide a device of the foregoing nature 20 which includes a resilient wire supporting member furnished with looped portions in which may be positioned a transparent tubular container that is adapted to house a slip of paper or designating label carrying the 25 identification marking of the tree, plant or shrub, the same being visible through the wall of said transparent container.

Furthermore, the wire supporting member is provided with an outwardly bent portion 30 that limits and supports a bottle in relation to the said supporting member when the same is positioned through the looped portions, the bottle or other transparent container being perfectly inserted therein with 35 the open end downward to prevent the elements attacking the identification slip or label contained therein. The article as a whole may be supported by penetrating the lowermost end of the wire supporting member 40 into the earth or other suitable location.

With the foregoing objects in view my invention consists essentially in the novel construction of transparent container supporting member hereinafter fully described and in the particular combination and arrangement of parts later on fully disclosed and more specifically defined by the appended claim.

In the further disclosure of the invention reference is to be had to the accompanying sheet of drawings constituting a part of this specification and in which like characters of reference designate the same or corresponding parts in all the views.

Figure 1—is an elevation of a potted

plant illustrating the application thereto of one practical embodiment of my invention.

Figure 2—is a fragmentary view to an enlarged scale illustrative of my novel label holder containing device and supporting means, the stem of the supporting means being broken away or in section.

Figure 3—is a perspective view of a suitable transparent container for containing the identification marking and data; and,

Figure 4—is a perspective view illustrative of the supporting member with the transparent identification label container shown in dot-and-dash lines in connection therewith.

By way of example I have illustrated my invention as applied in connection with a potted plant and from the drawings it will be readily seen that an ordinary pot is characterized by the numeral 5, said pot containing a plant 6 which may be of any rare or common variety which it is desirable to identify.

As illustrated my novel label holding device embodies in its entirety a supporting member 7 in which is adapted to be seated as later on explained a transparent label holding container such as a glass bottle 8, said bottle or container being of a nature 80 to conveniently house an ordinary label 9 on which is depicted or written the name and date or other information it is desirable to preserve in connection with the plant. My novel identification device 7 is conveniently formed from a length of wire 85 which is appropriately bent to provide a substantially circular end coil 10, an intermediate coil 11 and a supporting shoulder 12, said end and intermediate coils 10, 11, 90 being of a diameter to snugly house and contain the above referred to transparent container or bottle 8. The wire 7 at its upper portion is as stated formed to provide a means for firmly holding the tubular bottle 100 or container 8 for the identification slip or label 9 on which the history or other data relative to the plant is marked for further reference.

The bending of the wire to provide the supporting part 12 for the transparent container or bottle 8 is effected by bending under or turning an intermediate portion of the wire to provide the loop 11 as well as the shouldered portion 12 and the bottom length or shank 13 which may 110 be conveniently pointed or otherwise finished off for easy insertion into the ground. The

transparent or tubular container 8 is conveniently made of glass in the form of a small bottle having a closed end with the neck portion 14 thereof adapted to seat upon the aforesaid shoulder 12 so that it is effectually prevented from being forced into the ground or earth contained in the pot 5. In the use of my novel device for identifying plants, shrubs, bushes or the like, the transparent container 8 housing the identification slip 9 is positioned in the loop portions 10, 11, with the neck 14 downwards and in close abutment upon the shoulder 12, the resiliency of the loop portions 10, 11 serving to effect the secure holding of said container or bottle 8 against accidental displacement with relation to the wire supporting means 7. To remove the bottle or container 8 to change the identification marking slip 9 the bottle or container is clasped at its upper closed end and drawn outwards as will be clearly understood from an examination of the drawings.

From the foregoing description and an examination of the drawings it will be readily seen that by my invention I have provided a simple and very useful article for

the purposes specified and I wish it clearly understood that whilst there has been shown and described a preferred embodiment thereof of the same is susceptible of minor detail changes or variations and the right is hereby reserved to make such changes or alterations as fairly lie within the scope of the appended claim.

Having described my invention, what I claim as new and desire to secure by Letters Patent is:

In combination an identification label holder comprising a transparent tubular container adapted to enclose an identification label, a supporting means for said transparent tubular container consisting of a length of wire fashioned with an end loop, an intermediate loop and a laterally disposed supporting shoulder, said end and intermediate loops and the supporting shoulder being adapted to enclose and grip the transparent identification label container or tube, and an extension from the aforesaid shoulder that constitutes a supporting member for the device.

In testimony whereof I affix my signature.
FRANK F. SEIDTS.
